UNITED STATES PATENT OFFICE

2,221,832

MACHINE FOR ATTACHING FASTENINGS TO
ATTACHÉ CASES, TRUNKS, AND THE
LIKECharles William Cheney, Soho, Birmingham,
EnglandApplication November 25, 1938, Serial No. 242,218
In Great Britain November 27, 1937

7 Claims. (Cl. 1—4)

A fastening for an attaché case, trunk or the like usually comprises two members, the one a lock member and the other a hinged hasp member, to be attached to the body and lid respectively of the case.

A machine of the plunger-press type having upper and lower tools has been used for attaching a lock member having prongs, which, on the descent of the plunger, penetrate the material of the case and are clinched down. Such a machine is described and illustrated in the specification of applicant's United States Letters Patent No. 1,955,790. Heretofore, the hasp member had to be attached to the case by hand in proper position relative to the lock member.

The present invention has for its object to provide a plunger-press type machine for attaching a hasp member having penetrating and clinching prongs in proper position relative to a previously attached lock member by a single stroke of the plunger.

The invention provides a machine of the aforesaid type wherein each pair of tools comprises a positioning device arranged in alignment with a seating for a hasp member to be attached, said positioning device being adapted to engage a hole or a projection of the previously attached lock member, in combination with means for accurately positioning the lid longitudinally in correct relationship to the body.

The invention also combines with the aforesaid positioning device and longitudinal positioning means, an adjustable stop-gauge to determine the correct transverse position of the hasp member on the lid relative to the lock member on the body.

The invention will now be described with reference to the accompanying drawings which illustrate a machine for simultaneously attaching two hasp members to the lid of a case.

Fig. 1 is a front elevation of a machine according to the invention.

Fig. 2 is a side elevation of Fig. 1, partly in section.

Fig. 3 is an enlarged sectional plan of a portion of Fig. 1 on the dotted line A—A.

Fig. 4 is a sectional side elevation of a pair of tools at the end of the penetrating action and before clinching.

Fig. 5 is a front elevation of Fig. 4.

Fig. 6 is a side elevation of a modified form of the invention incorporating a stop-gauge.

Fig. 7 is a sectional plan of Fig. 6 on the dotted line B—B.

Referring to Figs. 1—5 inclusive, the frame

of the machine has rigid arms 2, 2 at its sides, and a rigid central tie bar 3, to immovably support a horizontally disposed anvil bar 4. A vertically projecting rigid pillar 5 supports a reciprocable plunger 6 to be operated by a lever 7 from a treadle action not shown.

At its lower end, the plunger 6 carries a horizontal pressure bar 8. Upon this pressure bar, there are mounted two upper tools 9, 9, while the anvil bar 4 carries two lower tools 10, 10. The tools 9, 9 and 10, 10, are adjustable along their respective bars. Each pair of upper and lower tools 9, 10 is fixed in its adjusted position, and both tool pairs operate simultaneously when the plunger moves downwardly.

All the aforesaid features are known, the action of the tools for penetrating and clinching being substantially in accordance with the prior patent referred to; the present invention concerns solely the relative positioning of the fastening members.

An attaché case 11 comprises a body 12 and a lid 13 hinged to the body at 14, said body having already attached thereto flat plate-like lock members 15, 15, a definite distance apart. Each lock member 15 comprises a casing 17 provided with a rectangular slot 16 and, within the casing, a slidable bolt 18 having a nose 19. The hasp members 20, 20 have each an attachment plate 21 to be attached to the lid 13 and a hasp 22 hinged to said plate and carrying a loop 23 for engagement with the bolt nose 19.

A rigid arm 24 formed with a slot 25 (Fig. 2) projects rearwardly from the back of each lower tool 10 and carries a positioning projection 26 of a shape corresponding to that of the loop 23 of the hasp member 20. The slot 25 renders it possible to adjust the position of the projection 26 on the arm 24 longitudinally, and said projection 26 is fixed after adjustment by means of a screw-nut 29.

Each lower tool 10 comprises two vertical side bars 27, 27, between which the upper tool 9 slides vertically. Also between the side bars 27 and below the upper tool 9, there is slidably mounted a carrier 28 having a seating 29 adapted to support a hasp member 20 to be attached to the casing, said seating 29 being in alignment with the positioning projection 26. The carrier 28 is urged upwardly against a stop (not shown) by means of a pressure spring 30. Each lower tool 10 has a vertically movable pressure plate 31 normally forced upwardly by a spring 32 and formed with holes 33, 33 having inclined walls 34, 34 and

arranged to be engaged by stationary clinching pegs 35, 35.

Slidably mounted on the anvil bar 4 on the outer sides of both lower tools 10, there are positioning blocks 36, 36. Each positioning block 36 is formed at its rear with a positioning angular abutment 37 adapted to be engaged by an edge of a side wall 38 of the case body 12, and at its front with a positioning gap 39 adapted to be engaged by the edge of a side wall 40 of the lid 13 of the case 11, said abutment 37 and gap 39 being so related that when the body 12 and lid 13 engage the same both body and lid are in correctly aligned positions for attaching the hasp member 20 to the lid.

Figs. 6 and 7 in which the same reference characters are used as in Figs. 1-5 to denote corresponding parts, illustrate the tools of a modified embodiment of the invention. The lower tool 10 of the modification is provided with a slidable stop-gauge 41 arranged transversely of the lower tool 10. The stop gage 41 comprises ascending rear posts 42, 42 adapted to co-operate with the longitudinal edge 43 of the case body 12, a depending front plate 44 adapted to co-operate with the inner face 45 of the lid 13, and side bars 46, 46 slidable in grooves 47, 47 in the lower tool 10. The positioning projection 26 is non-adjustable, and the hasp carrier 28 is formed as a vertically slidable pillar arranged centrally of the tools 9 and 10 and having upper and lower shoulders 48, 49 to co-operate with upper and lower faces 50 and 51, respectively, of the upper tool 9. The pillar 28 comprises further a peg 52 engaging a stationary limb spring 53 to provide frictional resistance to the vertical movement of said pillar.

The application of a pair of hasps to the lid of a case is performed in the following manner: First, a hasp member 20 is hand applied to each seating 29 in the carriers 28, 28 to be supported thereby. Then, the tools 9, 9 and 10, 10 are adjusted to their correct positions on their respective bars 8 and 4 and the positioning projections 26, 26 are also adjusted to their correct positions on the rigid arms 24, 24. Thereafter, a case 11, comprising a body 12, and a lid 13, hinged thereto at 14, and having a pair of lock members 15, attached to the body 12 a definite distance apart, is placed in the machine in upright and open condition with its body 12 disposed at the rear of the tools 9 and 10 and the lock members 15, 15 snap engaged with the positioning projections 26, 26. The positioning blocks 36, 36 are adjusted along the anvil bar 4 so that the angular abutments 37, 37 engage the respective side walls 38 of the body 12. The lid 13 of the case 11 is swung upwardly and inwardly by hand so that its longitudinal wall 55 rests on the pressure plates 31, 31 and its side walls 40, 40 engage the gaps 39, 39 whereby the lid 13 is now correctly aligned with respect to the body 12. In this position, in which the lid 13 is held by hand, the case 11 is supported solely by the positioning projections 26, 26 and the pressure plates 31, 31. The treadle mechanism is then operated, causing the upper tools 9, 9 to descend and, by means of shoulders 56, 56 abutting against the upper faces 57, 57 of the carriers 28, 28, to pick up said carriers so as to move the same downwardly. In this position, the undersurfaces 58, 58 of the tools 9, 9 rest upon the upper faces of the attachment plates 21, 21 for backing. Continuing the movement, the hasp prongs penetrate the lid 13 and are inclined towards each

other by the inclined walls 34, 34 until the attachment plates 21, 21 rest on the lid. Further downward movement of the plunger causes the pressure plates 31, 31 to descend against the action of the springs 32, 32 so that the pegs 35, clinch 5 the prongs.

The treadle mechanism is then released and the lock members 15, 15 are removed from the positioning projections 26, 26 by withdrawal of the bolts 18, 18, whereupon the entire case 11 10 can be removed with the hasp members 20, 20 attached to the lid 13 in correct longitudinal relationship, with respect to the lock members 15, 15.

The operation of a machine embodying mechanism according to Figs. 6 and 7 differs from that 15 previously described in that the inner face 45 of the lid 13 is pressed against the front plate 44 of a stop-gauge 41 to slide the same from its forward position indicated in dotted lines rearwardly until its rear posts 42, 42 abut against the 20 longitudinal edge 43 of the body whereby the lid 13 is correctly positioned transversely for attaching the hasp members 20, 20 thereto.

The terms hasp and lock and body and lid are 25 interchangeable.

The invention may be successfully employed in an instance where two engaging and disengaging complementary members are to be attached in correct relationship, one member to one part of the case and the other member to the other 30 part of the case. If the lock member has a circular hole in its front plate, the positioning projection would be equivalent to the notched peg provided upon the hasp member to ordinarily engage this hole, if there is a projecting stud on 35 the lock member and a corresponding hole to engage said stud in the hasp member, the positioning projection would be formed with a hole to engage the stud.

Having now described my invention what I 40 claim and desire to secure on Letters Patent is:

1. A machine for attaching hasps to attaché cases consisting each of a lid portion and a body portion, the latter being provided with a lock member, said machine comprising a frame, a 45 plunger reciprocably mounted on said frame, an upper tool carried by said plunger, a lower tool supported on said frame for cooperation with said upper tool, said upper and lower tools being adjustable lengthwise of said frame, a seating 50 for a hasp on one of said tools, and a positioning device carried upon one tool in alignment with said seating, said positioning device being adapted to engage the lock member on the body portion of the case. 55

2. A machine, as claimed in claim 1, comprising means carried by said frame and hand adjustable thereon to accurately position the lid portion of the case in relation to its body portion.

3. A machine, as claimed in claim 1, comprising a stop gauge carried by one of said tools for adjustment transversely thereof to determine the correct transverse position of the hasp member on the lid to the lock member previously attached 65 to the body.

4. A machine, as claimed in claim 1, in which said lower tool comprises a vertically movable carrier in which the hasp seating is formed, and a rearwardly projecting arm mounted on a fixed 70 part of said lower tool and carrying said positioning device.

5. A machine, as claimed in claim 1, comprising a positioning block carried by and longitudinally adjustable with respect to said frame, said positioning block being shaped to cooperate with 75

the body portion and the lid portion of the case for correct relative positioning of the one to the other.

6. A machine, as claimed in claim 1, comprising a longitudinal anvil bar mounted rigidly on said frame, and means to position the lid portion of the case in relation to its body portion, said lower tool and positioning means being carried longitudinally slidably by said anvil bar.

7. A machine, as claimed in claim 1, in which one of said tools comprises guide means engaging the other tool to allow only vertical movements of one tool relative to the other, whereby the two tools form a pair which is longitudinally 5 adjustable as a unit.

CHARLES WILLIAM CHENEY.
